UNITED STATES PATENT OFFICE.

PHILIP JACKSON DARLINGTON, OF NEW BRITAIN, CONNECTICUT.

ROTARY MOTOR.

No. 914,022.

Specification of Letters Patent. Patented March 2, 1908.

Application filed November 6, 1908. Serial No. 461,409.

To all whom it may concern:

Be it known that I, PHILIP JACKSON DARLINGTON, a citizen of the United States, residing at New Britain, in the county of Hartford and State of Connecticut, have invented certain new and useful Improvements in Rotary Motors, of which the following is a specification, reference being had therein to the accompanying drawing.

10 This invention relates to motors, and more particularly to motors arranged to be passed through boiler tubes and the like for the purpose of driving tools to remove scale therefrom, although it may be used for other purposes.

15 The particular object of the invention is to provide a motor which is capable of operation by steam or compressed air, which is powerful, compact, simple and cheap of construction, efficient, durable and easily repaired.

20 With these and other objects in view the invention consists in the novel construction, arrangement and combination of parts as hereinafter described and claimed.

25 In the accompanying drawings:—Figure 1 is a longitudinal section through a motor embodying my invention. Fig. 2 is a transverse section on line 2—2 of Fig. 1. Fig. 3 is a longitudinal section taken at right angles to the section of Fig. 1 and with the piston and socket-ring removed. Fig. 4 is a view looking at the rear end of the motor with the socket-ring removed. Fig. 5 is a longitudinal section on the line 5—5 of Fig. 2, and with 30 piston, bushes, and socket-ring removed. Fig. 6 is a transverse section on the line 6—6 of Fig. 5. Fig. 7 is a longitudinal section of a modified construction. Fig. 8 is a transverse section on line 8—8 of Fig. 7. Figs. 9, 10 and 11 are longitudinal sectional views showing modified constructions for use in cleaning bent-tubes.

35 In the drawings, 1 represents a cylinder, 2 is a front head, 3 is a rear head, 4 is a socket-ring, and 5 is a fluid supply pipe. 1, 2, 3 and 45 5 are all formed with smooth exterior of circular outline of transverse section at all points, all externally concentric with each other and joined together with fluid tight transverse joints. Cylinder 1 and head 2 are

formed with eccentric cylinder bores 6 and 7 respectively. A rotary longitudinal slotted piston 8, with reduced front and rear journal portions 9 and 10 respectively, is supported concentrically with the exterior of cylinder 1 and contacts along a line with the curved walls of cylinder bores 6 and 7. Cylinder 1 has an admission longitudinal port 11 formed in its wall and extending from its front to its rear face, and an admission radial port 12 formed in its front face and communicating from port 11 to bore 6. Front head 2 has an exhaust longitudinal port 13 formed in its wall from its rear to its front face and an exhaust radial port 14 formed in its rear face and communicating from port 13 to bore 7. Admission radial port 12 and exhaust radial port 14 communicate with bores 6 and 7 respectively at angular positions about 90° apart and on opposite sides of the line of contact of said bores with piston 8. A blade 15 is loosely carried by and slides in the slot of piston 8 as it revolves. The blade 15 contacts in all positions, at both sides and both edges with bores 6 and 7.

75 Rear head 3 is formed with a circumferential fluid space 16, a longitudinal delivery port 17 communicating therefrom to the front face of head 3 at a position opposite port 11, a plurality of longitudinal receiving ports 18 communicating to space 16 from the rear face of head 3, a hollow central hub 19 and longitudinal outwardly extending radial ribs 20 therefrom. Socket-ring 4 is internally threaded and screwed over ribs 20 forming fluid passages between them registering with ports 18. Socket-ring 4 is formed with a fluid chamber 21, has a straining disk 22 across chamber 21 resting on an internal shoulder 23 therein, and makes fluid tight transverse joint between its front face and the rear face of head 3. The rear end of socket-ring 4 is internally formed with a conical or part spherical socket surface 24, tapering toward the rear. Supply pipe 5 is 95 formed with an external part spherical or ball surface 25 at its rear end of larger maximum diameter than the smallest diameter of surface 24 forming universal fluid tight tension coupling joint with surface 24.

26 is a front bush seated in head 2 and rotatably supporting piston 8 by journal portion 9.

27 is an annular balance pocket formed in 5 the rear face of bush 26 under the shoulder of piston 8.

28 is a passage communicating from admission port 11 to pocket 27 to admit lubricant and fluid under pressure thereto for 10 lubricating and balancing respectively the piston 8 and its forward thrust.

29 is a rear bush seated in head 3 and rotatably supporting piston 8 by journal portion 10.

15 30 is an annular oil distributing passage around and adjacent to journal portion 10.

31 is a radial oil hole leading to passage 30 from an annular oil distributing passage 32 formed partly in the outer cylindrical surface 20 of bush 29 and partly in the inner cylindrical surface of the seat for bush 29 in head 3.

33 is an oil passage communicating to passage 32 from exhaust port 13 forming with passages 30, 31 and 32 a continuous passage 25 through which oil poured in exhaust port 13 will flow to journal portion 10 when the motor is held front end up.

34 is a shoe ring of external diameter slightly less than the bore of the tube to be 30 cleaned, fitted over the front end of head 2 to an external shoulder on head 2 and is formed with an internal flange 35 forming an internal shoulder 36.

37 are long screws with heads overhanging 35 and bearing upon shoulder 36, passing through head 2, cylinder 1 and threaded into head 3.

38 is a central hub in pipe 5 with a part spherical socket concentric with the part 40 spherical end thereof and carried on ribs 39.

40 is a part spherical headed screw bearing in the socket of hub 38 and forming universal joint therewith.

42 is a hub formed concentric on head 3 45 threaded to adjustably receive screw 40.

41 is a lock-nut to secure screw 40 as adjusted to hold pipe 5 freely but snugly into the socket of ring 4 in all angular positions of pipe 5.

50 The operation is as follows:—Fluid under pressure enters from a supply hose through pipe 5, enters the cylinder bores 6 and 7, behind blade 15 revolving piston 8 and escaping by exhaust port 13. A suitable tool is 55 attached to the front end of piston 8. The motor and tool are advanced through the tube on the end of a flexible supply hose removing scale from in front of ring 34. The fluid pressure maintains contact between 60 socket-ring 4 and supply pipe 5 which swivels in socket surface 24 to adjust itself to bends in the tube being cleaned. Strainer

22 catches pieces of hose lining or other obstruction that might otherwise block and stop the motor.

65

What I claim is:—

1. In a rotary motor, the combination with a slotted piston, of a casing member formed with a cylindrical bore open at one end and closed by an integral end wall at the other end, said member being formed with a longitudinal port in its wall and a radial port in its end face.

2. In a rotary motor, the combination with a slotted rotary piston, of a cylinder 70 having a radial port formed in its end face, and a head whose end face bridges over and completes said port.

3. In a rotary motor, the combination with a slotted piston, of a cylinder, a concentric fluid supply pipe formed with an externally part spherical end, a concentric ring member surrounding and forming fluid tight universal joint with said part spherical end, said ring member being internally threaded 80 for attachment to said cylinder and screwed over external ribs thereon.

4. In a rotary motor, a ring member with an internal swivel socket at one end and a strainer across its bore.

90

5. In a rotary motor, the combination with a slotted piston, of a cylinder, a supply pipe formed externally at one end with a part spherical surface and a concentric ring member formed internally at one end to fit 95 and make universal joint with said part spherical surface of said supply pipe and at the other end internally threaded for attachment to the said cylinder over external ribs and forming fluid passages between 100 them.

6. In a rotary motor, a ring member formed at one end with an internal socket and at the other end with an internal screw thread, and a cylinder head with external 105 longitudinal ribs externally threaded and screwed into said internal thread.

7. In a rotary motor, the combination of a cylinder head with outwardly extending longitudinal ribs, a ring member secured externally over said ribs, and a concentric supply pipe with a part spherical end forming hollow universal joint with said ring member.

110

8. In a rotary motor, a member of circular 115 transverse section, formed with a circumferential space having a plurality of receiving ports leading thereto from one end face and a delivery port leading therefrom to the other end face.

120

9. In a rotary motor the combination of a cylinder head, of circular transverse section formed with a circumferential fluid space and having outwardly extending longitudi-

nal radial ribs, a ring member screwed over said ribs and a supply pipe secured to said ring member.

10. In a rotary motor, the combination of 5 a piston, a head rotatably supporting said piston, and formed with longitudinal external ribs, a ring member secured outside of and around said ribs forming longitudinal fluid passages between them, said head being

formed with a circumferential fluid space 10 and receiving ports registering with the space between said ribs.

In testimony whereof I affix my signature in presence of two witnesses.

PHILIP JACKSON DARLINGTON.
